STEWART ASSIGNOR TO SAID COLMAN

OPERATING MEANS FOR DOORS AND THE LIKE

Application filed October 4, 1926. Serial No. 139,277.

Our invention relates to closure operating mechanisms, and more particularly to power-driven operators of the type employed in opening and closing garage or factory doors. 5 It frequently happens, especially in the case of large garage doors, that it is necessary or desirable to use the main door closing the vehicle passageway to enable a person to enter or leave the building. In such 10 cases it is unnecessary and undesirable, especially in cold weather, to operate the door into wide open position. Furthermore, the operation of the door into the wide open position requires a second operation of a control device to effect the closing of the door.

The general object of the present invention is to provide a novel power-operating mechanism for closure members such as doors, having a power unit and control mechanism 20 therefor operable selectively to cause the door to be moved into either wide open position or partially open position.

Another object is to provide in conjunction with a power mechanism for opening 25 and closing a door, together with the main control device therefor, a secondary control device adapted to cause the door to be opened only partially for a predetermined interval of time and then to be closed automatically 30 without further attention. With this arrangement, the consumption of power by the door operating mechanism is minimized, and the person entering or leaving the building is relieved of the responsibility of closing 35 the door.

Other objects and advantages of the invention will become apparent from the following detailed description taken in connection with the accompanying drawings, in 40 which

Figure 1 is an elevational view of a door operating mechanism embodying the features of our invention.

Fig. 2 shows diagrammatically the arrangement of electrical circuits for control-

ling the electric motor which is used as the power unit in the preferred embodiment of the invention.

Fig. 3 is an elevational view of a delay action device for controlling one of the motor switches. 50

Figs. 4 and 5 are respectively plan and side views of one of the limit switches.

While we have shown in the drawings and will herein describe one embodiment of the 55 invention, it is to be understood that we do not intend thereby to be limited to the particular form disclosed, but aim to cover all modifications and alternative constructions falling within the spirit and scope of the invention as expressed in the appended claims. 60

The mechanism shown in the drawings to illustrate the present invention comprises generally a door, an electric motor for supplying power to open and close the door, two 65 motor switches each controlling the opening of the door, a motor switch controlling the closing of the door, and a control device operated by the door during the opening movement and arranged to operate said closing 70 switch automatically after a predetermined interval of time provided the door has been opened by a certain one of said opening switches.

The closure member and the operating 75 means therefore may be of any preferred construction. In the present instance, a door having two sections 10 and 11 is employed, each section being slidably supported by brackets 12 on a stationary track 13 mounted on the inner wall 14 of the building above the doorway therein. The operating mechanism includes a long screw-threaded shaft 15 journaled at opposite ends in bearing brackets 16 and driven by an electric motor 17 80 through suitable gearing located in a housing 18. Rigidly mounted on the inner side of each door section is an upright bar 19 having a member 20 at its upper end threaded onto one end of the shaft 15. The oppo- 85

site ends of the shaft 15 are reversely threaded so that upon rotation of the shaft in one direction, the members 20 will travel away from each other to open the door and upon reverse rotation, the door will be closed. 5
Stops 21 are provided on the shaft to limit the outward movement of the door sections in the event that the sections are not stopped by the limit switches as will be described later. 10

To control the direction of rotation of the motor 17 and thereby the normal opening and closing of the door, electromagnetic switches 22 and 23 (see Fig. 2) are provided for connecting the terminals 24 and 25 of the power line to the motor and to control the direction of current flow in the motor armature 26 relative to that in the motor field 27. The opening switch 23 is located in a switch box 28 (see Fig. 1) and comprises three normally open contact switches 23^a, 23^b and 23^c, each having a stationary contact and a movable contact mounted on a pivotal arm 23^d which is arranged to be moved to close the three 25 contact switches simultaneously by energization of a magnet 23^e and to be returned to open position by a spring 23^f when magnet 23^e is deenergized. Switches 23^a and 23^b control the application of the line voltage to the 30 motor armature and field, while the switch 23^c controls a locking circuit for connecting the magnet across the power line to hold the contact switches closed.

The closing switch 22 is also located in 35 the box 28 and its construction is identical with that of the opening switch 23, the line connections of the switches 22^a and 22^b with the armature 26 being reversed to those of switch 23 so that the direction of rotation 40 of the motor may be reversed. A normally closed limit switch 29 mounted on the wall 14 is included in the locking circuit of the electromagnetic switch 23 with its movable arm 30 (Fig. 1) positioned to be struck by 45 the member 20 when the door section 10 has been completely opened. When this occurs, the switch 29 will be opened, and the magnet 23^e will be deenergized, the arm 23^d returning to normal position, thereby cutting off 50 the power supply to the motor. A similar limit switch 31 is interposed in the locking circuit of the electromagnetic closing switch 22 and is arranged to be opened by the member 20 as the door section 10 approaches its 55 closed position.

Located at various places about the building are hand-operated switches 32 for selectively controlling the operation of the electromagnetic switches 22 and 23. Preferably, 60 each of these switches has four push buttons 34, 35, 36 and 37, buttons 34 and 35 being mounted on a pivoted arm 38, and buttons 36 and 37 being mounted on a pivotal arm 39 which is held in normal position by springs 65 40. The arm 38 is connected to the power

terminal 25 and is adapted to be moved by the button 34 against a contact 41 connected to the energizing circuit for the magnets 22^e and 23^e through a current limiting resistance 41^a. Normally the arm 38 is in the 70 position shown in Fig. 2. When it is desired to stop the door manually while it is being opened or closed, the button 35 is pushed to break the locking circuit of the electromagnet then energized. The arm 39 is connected to the other power terminal 24, and is adapted to be moved selectively against contacts 42 and 43 to connect the power terminal to either of the magnets 22^e and 23^e momentarily, or until the locking circuit of 80 the magnets is established by movement of the corresponding switch arm.

The operation of the switches in opening the doors full width from the closed position shown in Fig. 1, and then in closing them, 85 will be briefly described. To open the door sections, the button 36 is pushed. This momentarily energizes the magnet 23^e which moves the arm 23^d to close the switches 23^a and 23^b thereby starting the motor and establishing the locking circuit through switch 23^c for the magnet 23^e. Rotation of the motor moves the door sections apart to open the doorway. As the sections approach their open positions, the limit switch 29 is opened 90 which breaks the locking circuit of magnet 23^e thereby cutting off the current supply to the motor stopping the door sections automatically.

To close the door, the button 37 is pushed 100 which causes arm 22^d of the closing switch 22 to establish connections for the reverse rotation of the motor and also for locking the circuit through the limit switch 31, which, it will be observed, was closed automatically 105 in the initial opening movement of the doors. The limit switch 31 is opened as the door sections approach their closed position.

The switch control mechanism thus far described is intended for use in completely 110 opening the doors so as to permit automobiles, trucks and the like to enter. We shall now explain the mechanism for controlling the motor circuits so that the doors may be partially opened for a brief interval to permit a person to enter or leave the building.

To these ends an auxiliary opening switch 44 constructed in the same manner and connected to the power terminals in the same way as the opening switch 23 is located within 115 a switch box 45. The magnet circuit of this switch is adapted to be closed manually by one of two switches 46 and 47 of the push button type which, in the present instance, are conveniently located on the inner and outer sides of one of the door sections. A snap switch 48, located inside of the door, is interposed in series with the outside switch 47 so that opening of the door from the outside may be prevented if desired. To pre- 120

6 vent operation of the auxiliary switch 44 by the control switches 46 and 47 when the door is moving to its closed position, switches 49 are provided which are closed only when the door is closed. For this purpose, spring contacts 50 (see Fig. 1) are mounted on the wall 14 and bear against contacts fixed on the outermost edge of the door section 10 to complete the circuit through switches 46 and 47 when the door is in closed position. As soon as the door sections begin to move apart, the switches 47 will be opened.

10 Interposed in the locking circuit of the auxiliary switch magnet 44^e is a limit switch 51 arranged to disconnect the motor from the power line and thereby arrest the movement of the door sections after they have been moved a predetermined distance apart, this distance being determined by the position of the limit switch 51 on the wall 14. The limit switch employed for this purpose and shown in detail in Figs. 4 and 5 comprises a bracket 52 fixed to the wall 14 and carrying an outwardly projecting pivotal lever 53 having a contact arm 54 carrying a contact piece 54^a which is normally held closed against two contacts 55 by a spring 56. When the door has been moved open a predetermined distance, a cam 57 carried by the door section 10 strikes the lever 53 and breaks the contacts thereby stopping the door.

15 The means for automatically closing the door after it has been partially opened by operation of the auxiliary electromagnet switch 44 as distinguished from the regular opening switch 23 comprises a circuit 58 including a switch 59 in parallel with the control switch for the regular closing switch 22 and a delay action device 60 for automatically closing the switch 59 after allowing a predetermined interval of time for the motor to come to rest after the limit switch 51 has been opened. It will be apparent that when the switch 59 is closed, the closing switch 22 will be operated to start the movement of the door sections to their closed positions. A limit switch 61 of the same construction as switch 51 is interposed in the circuit 58 as a safety and is positioned on the wall 14 just beyond the limit switch 51, so as to prevent closure of the switch 22 by the delay action device when it is intended that the doors be opened their full width. It will be observed therefore that the limit switch 61 is always closed except 20 when the door is opened beyond the distance determined by the position of the limit switch 51, that is, beyond the predetermined partially open position.

25 The device 60 for delaying the closing of the switch 22 comprises, in the present instance, a balanced wheel 62 which in effect constitutes a compound pendulum. This wheel is supported by a knife-edge bearing 63 on a horizontal bracket 64 mounted on the 30 wall of the building. Projecting laterally

from the peripheral portion of the wheel above the bracket are two rigid pins 65 and 66 which serve to limit the rotational movement of the wheel. When the wheel oscillates counter-clockwise, the pin 65 strikes a spring contact 67 of the normally open switch 59 thereby closing the switch which initiates the operation of the closing switch 22 as above described. The wheel is set in motion by a cam 68 (Fig. 1) mounted on a bar 69 which projects horizontally from the door section 10 and rests slidably on a track 70. The cam 68 is positioned to strike a lateral arm 71 pivoted on the wheel 62 to swing on a radially extending axis. An arm 72 rigid with the arm 71 prevents pivotal movement of the arm 71 by the cam 68 when the door is being opened, but permits the cam to move past the arm without overcoming the inertia of the wheel when the door is being closed.

35 To summarize the operation, a person desiring to enter or leave the building when the door is closed pushes one of the control switches 46 or 47 which closes the circuit through the normally closed limit switch 51 and the switches 49 thereby energizing the magnet 44^e of the auxiliary opening switch 44. This starts the motor which moves the door sections apart. In the movement of the section 10, the cam 68 strikes the arm 71 on the wheel 61 and gives the wheel an impetus in a clockwise direction. Such movement of the wheel is arrested when the pin 66 strikes the bracket 64, and the wheel, acting as a compound pendulum, starts to rotate slowly 40 in a counterclockwise direction. The door section continues to move apart until section 10 opens the limit switch, the motor being thereby stopped with the door partially open. The person may then enter or leave the building.

45 In the slow counter-clockwise movement of the wheel 62, the pin 65 strikes against the contact 67 which closes the switch 59 and thereby energizes the magnet 22^e to operate the closing switch 22. The door will then be closed in the usual way. It will be noted that the interval between the opening of the switch 44 and the closing of the switch 22 will be determined by the position of the pin 65, and the period of oscillation of the pendulum, this interval being adjusted so as to permit a person to enter or leave the building safely and also to allow the motor to come to rest before the power connections are reversed.

50 The auxiliary control unit thus provided is extremely simple in construction and efficient in operation. It can be adapted to practically any type of power driven mechanism such as is used for operating doors and does not interfere in any way with the operation of the door by the regular opening and closing switches.

55 We claim as our invention:

1. A door operating mechanism having, in

- combination with a door, a motor, mechanism driven by said motor to operate the door, a power line, three electro-magnetic switches for connecting said power line to said motor, 5 one of said switches being arranged to control the closing of the door, said other switches being arranged for independent operation to open said door, and a device for operating said closing switch automatically a predetermined interval after the operation of the door 10 by one of said opening switches. 70
2. A door operating mechanism having, in combination with a door, an electric motor operatively connected to the door, two manually operable switch devices for controlling said motor, one arranged to cause the door to be moved into one position and the other arranged to cause the door to be moved into a position beyond said first mentioned position, an electro-magnetic switch controlling 15 said motor to return the door to its initial position, two switches connected in parallel and each adapted to operate said last mentioned switch and means to operate one of 20 said switches automatically after the door has stopped in said first mentioned position. 80
3. A door operating mechanism having, in combination with a door, a motor operatively associated with the door, a switch for controlling 25 said motor to completely open said door, a second switch controlling said motor to partially open the door, and a control switch operable to cause the door to be closed automatically from its partially open position, and a switch interposed in the circuit of said 30 control switch and positioned so as to be opened by said door in moving from its partially open position to its completely open position. 85
4. A door operating mechanism having, in combination with a door, a motor arranged to operate the door, selectively operable switching mechanism for controlling said motor to completely or partially open the door, an electro-magnetic device controlling said motor to 35 close the door automatically, and a switch interposed in series with said device and arranged to be opened after the door has been opened beyond said partially open position. 90
5. A door operating mechanism having, in combination with a door, a motor, a primary electro-magnetic switch adapted to control 40 said motor to open the door, a secondary electro-magnetic switch adapted to control the opening of said door, a control switch mounted on said door and adapted to operate said secondary electro-magnetic switch, and means operating automatically after the door has been opened by said secondary switch to control 45 said motor whereby to close the door. 95
6. A door operating mechanism having, in combination with a door, a motor, a switching device controlling the motor to initiate movement of the door from closed position to an 50 open position, a second switching device controlling the motor to initiate the movement of the door from closed position to another open position, a switching device for causing the door to be moved back to its closed position automatically after reaching said first mentioned position, and means operable in the movement of the door to said last mentioned position for preventing the control of the motor by said last mentioned switching device. 100
7. A mechanism of the character described having, in combination, a closure member, an electric motor arranged to move said member in opposite directions, three switches controlling the operation of said motor, two of said switches being arranged for independent operation to cause the motor to move said member in one direction, said other switch being arranged for automatic operation to cause the motor to move said member in the opposite direction. 105
8. An operating mechanism having, in combination with a door, power means to open and close the door, selectively operable means controlling said power means to partially or completely open the door, means to stop said door when in partially opened position, and a device actuated by said door while the door is being moved to said partially opened position and operative to control said power means whereby to close the door automatically. 110
9. An operating mechanism having, in combination with a door, power means for moving said door, means operable to control said power means to completely open the door, means operable to control said power means to partially open the door, and a device operable to control said power means whereby to close the door automatically provided the door has been opened by said last mentioned control means. 115
10. An operating mechanism having, in combination with a door, power means to open and close the door, two independently operable devices controlling said power means to open the door, and means rendered active during opening of said door by a predetermined one of said devices for initiating the operation of said power means to close the door automatically. 120
11. An operating mechanism having, in combination with a door, power means to open and close the door, two independently operable devices controlling said power means to open the door, means rendered active during opening of said door by one of said devices and operating to close the door automatically, and a device for delaying the effective operation of said last mentioned means. 125
12. An operating mechanism having, in combination with a door, power means to open and close the door, a device adapted to cause the door to be completely opened, a de- 130

vice adapted to cause the door to be partially opened, means controlling said power means to close the door automatically, and means for rendering said control means ineffective when the door is opened by said first mentioned device.

13. An operating mechanism for the character described having, in combination with a closure member, a rotary power device operatively associated with said member whereby the direction of rotation of said device determines the direction of movement of said member, manual control means operable to cause said power device to rotate in one direction, means for stopping said power device, and a delay action device arranged to cause reverse rotation of said power device after a predetermined interval following the operation of said stopping means.

14. An operating mechanism of the character described having, in combination with a closure member, a rotary power device operatively associated with said member whereby the direction of rotation of said device determines the direction of movement of said member, manual control means operable to cause said power device to rotate in one direction, mechanism for stopping said power device, means operable to initiate rotation of the motor in the opposite direction, and means for delaying the action of said last mentioned means until said motor has come to rest or substantially so.

15. In a mechanism of the character described, the combination of a rotatable power device, control means operable to cause rotation of said power device for a predetermined interval in one direction, secondary means operable to cause rotation of said device in the same direction for a predetermined shorter interval, and means operating automatically in response to the rotation of said device by said secondary control means for reversing the direction of rotation of said device.

16. A door operating mechanism having, in combination with a door, an electric motor operatively associated with the door, a primary opening switch controlling the operation of said motor to open said door full width, an auxiliary opening switch controlling said motor to partially open the door, a closing switch, and a control switch interposed in the circuit of said auxiliary switch and operable automatically to prevent operation of said motor by said auxiliary switch while the door is being closed by operation of said closing switch.

17. A door operating mechanism having, in combination with a door, an electric motor, two switches adapted for independent operation to control said motor whereby to open the door different distances, a switch controlling the closing of said door, and means for preventing effective operation of one of

said opening switches when the door is being closed under the control of said closing switch.

18. A door operating mechanism having, in combination with a door, a power means arranged to operate said door, two devices adapted for selective independent operation to control the opening of said door different distances by said power means, a device for causing the door to be closed, and means to prevent the effective operation of one of said opening devices during operation of the door by said closing device.

19. A mechanism for operating the door of a building having, in combination with a door, an electric motor operatively associated with said door, an electromagnetic switch for controlling said motor to open said door, a circuit controlling the operation of said electromagnetic switch including a manually operable switch located within said building, and a circuit in parallel with said manually operable switch and including two switches, one located outside of the building, and the other located within the building.

20. A mechanism of the character described having, in combination with a door, an electric motor, a switch for controlling the motor to close said door, and a balanced wheel for closing said switch, said wheel being actuated by said door in moving into open position.

21. A mechanism of the character described having, in combination with a door, power means for opening and closing the door, means for controlling said power means to cause the door to be opened, means for reversing the movement of said power means whereby to close the door, and means rendered active during opening of the door for delaying the effective operation of said reversing means until said door has come to rest.

22. An operating mechanism having, in combination with a door, a motor operatively associated with the door, switching mechanism controlling said motor to open the door, a manually operable switch controlling said motor to close the door, a switch in parallel with said manually operable switch, and means actuated by said door in moving to open position for operating said last mentioned switch automatically.

23. The combination with a closure member, of a power driven operating means for said member, a control mechanism selectively operable to initiate an operating cycle of said operating means to cause said member to move either into wide open position or into partially open position, means controlling said operating means to cause said member to be closed from either of said positions, and means operating automatically after said member has been stopped in said partially open position to initiate the

operation of said last mentioned means.

24. The combination with a closure member, of a power driven operating means for said member, and a control mechanism operable to cause said member to move into wide open position, said mechanism having an auxiliary control device operable to cause said member to move into partially open position and then automatically into closed position.

25. The combination with a door to be operated, of an electric motor operatively associated with said door, two circuits each adapted to control the starting of said motor to open said door, a switch in one of said circuits adapted to be operated whereby to stop said motor when the door has been moved a predetermined distance, a switch in said other circuit adapted to be operated to stop the motor when the door has moved a predetermined shorter distance, a circuit controlling the operation of said motor to close said door from either of said positions, and means operating automatically after said door has been stopped in said last mentioned position to control said last mentioned means whereby to restart said motor.

26. The combination with a closure member, of a power driven operating mechanism including an electric motor, two selectively operable control means adapted to initiate the operation of said motor to open said member, means responsive to the operation of said member by one of said control means to stop said motor with said member in partially opened position, means responsive to the operation of said member by said other control means to stop said motor with said member in wide open position, and means responsive to the operation of said first mentioned control means and operable automatically to restart said motor to close said member after the member has stopped in its partially open position.

27. The combination with a closure member, of a power driven operating mechanism including an electric motor, two selectively operable control means adapted to initiate the operation of said motor to open said member, means responsive to the operation of said member by one of said control means to stop said motor with said member in partially opened position, means responsive to the operation of said member by said other control means to stop said motor with said member in wide open position, means responsive to the operation of said first mentioned control means and operable automatically to restart said motor to close said member after the member has stopped in its partially open position, and means operable after said member has reached said partially open position to relay the action of said last mentioned means.

28. The combination with a door, of a

power driven operator therefor including an electric motor, and control means for said motor operable selectively when the door is in closed position to initiate either a single door opening cycle of said operator or a combined door opening and closing cycle.

In testimony whereof we have hereunto affixed our signatures.

HOWARD D. COLMAN.
DUNCAN J. STEWART.
